P. D'H. DRESSLER

KILN CAR

Original Filed April 7, 1920

Fig. 5. Philip D'H. Dressler
By his Attorney
John E. Lubbell

UNITED STATES PATENT OFFICE.

PHILIP D'H. DRESSLER, OF ZANESVILLE, OHIO, ASSIGNOR TO AMERICAN DRESSLER TUNNEL KILNS, INC., OF NEW YORK, N. Y., A CORPORATION OF NEW YORK.

KILN CAR.

Application filed April 7, 1920, Serial No. 371,903. Renewed May 31, 1924.

To all whom it may concern:

Be it known that I, PHILIP D'H. DRESSLER, a subject of the King of Great Britain, and resident of Zanesville, in the county of 5 Muskingum and State of Ohio, have invented certain new and useful Improvements in Kiln Cars, of which the following is a specification.

The object of the present invention is to 10 provide an improved construction of the refractory body portion of the cars employed in transporting goods through tunnel kilns, which will be relatively simple in construction and will be durable under the 15 severe conditions, and particularly under the contraction and expansion of the parts to which such cars are subjected in regular operation.

The various features of novelty which 20 characterize my invention are pointed out with particularity in the claims annexed to and forming a part of this specification. For a better understanding of the invention, however, and the advantages possessed by 25 it reference should be had to the accompanying drawings and descriptive matter in which I have illustrated and described a preferred embodiment of my invention.

Of the drawings:

30 Fig. 1 is a sectional elevation of the car, the section being taken on the broken line 1—1 of Fig. 3.

Fig. 2 is a section taken on the line of 2—2 Fig. 1.

35 Fig. 3 is a plan view of the car shown in Fig. 1.

Fig. 4 is a section taken similarly to Fig. 1 illustrating a modified structure.

40 Fig. 5 is a section on the line 5—5 of Fig. 4; and

Fig. 6 is a perspective view of a detail of construction employed in the car shown in Figs. 4 and 5.

45 In the drawings and, referring first to the construction shown in Figs. 1, 2 and 3, A represents a metallic frame member forming the bottom of the car body and preferably made as a one piece steel casting.

As shown, the frame member comprises an 50 upstanding marginal flange A¹, and strengthening ribs A² on its upper side. The usual wheels B are journaled in the member A, and the latter is provided, as shown, with a concrete filling C which extends to the level 55 of the tops of the ribs A² but has its upper

surface somewhat below the upper edge of the marginal flange A¹. Seated on the concrete layer C are a plurality of massive refractory blocks. As shown there are four of these blocks, D, D¹ and D². As 60 shown these blocks are rectangular in outline, and each extends the full width of the car. Each of these blocks which are hollowed out, comprises vertical plate like portions or webs d extending transversely 65 to the length of the car, and plate like portions or webs d¹ and d² integrally connecting the block portions d. Mounted on the tier of blocks D, D¹ and D², is a second tier of refractory blocks E, E¹, E², E¹ and 70 E which are also rectangular in outline and extend each the full width of the car. Each of the blocks E, E¹, E², E¹ and E, which are hollowed out, comprises vertical portions e extending transversely to the 75 length of the car, and portions e¹, e², and e³ integrally connecting the portions e. In addition each of the blocks E, E¹, E² and E is formed with an integral web portion e³, which closes the upper end of each of 80 the cavities or chambers formed in the blocks between the walls e, e¹ and e², except that each of those cavities has a tapered opening through the corresponding web portion e³ which is normally closed 85 by a refractory plug F. The upper edges of the central web portion D², of the blocks D, D¹ and D², is formed with a channel d³ in its upper edge, which advantageously is laterally enlarged to receive rib portions 90 e⁴ formed on the lower sides of the corresponding portions e² of the blocks E, E¹ and E². The channels d³ terminate, adjacent the opposite ends of the car, in shoulders d⁴, and the rib portion e⁴ of the end 95 blocks E are correspondingly shortened so that in the assembled structure, the ends of these rib portions shut against the shoulders d⁴. The web portions d¹ of the refractory blocks D, D¹ and D² are rabbed 100 as indicated at d⁵ to receive the lower ends of the web portions e¹ of the blocks E, E¹ and E².

Mounted on the upper side of the tier of 105 blocks E, E¹, E², E¹ and D are a series of spaced apart transverse girders G, each of which extends the full width of the car and is a one piece block of refractory material. Mounted on the tops of the girders G is the usual platform composed of large suitably 110

shaped slabs H of refractory material formed with openings h^1 to permit the flow of the kiln atmosphere through the roof, formed by the slabs H, for the open ended 5 channels between the various girder blocks G. As shown the block D is formed at the end of the car, with an outstanding horizontal rib d^6 which enters the correspondingly located groove d^7 formed in the end block 10 D² of an adjacent car. The cavities in the blocks D, D¹ and D² are advantageously filled with a suitable insulating material, such as kieselguhr, and this is true also of the cavities in the blocks E, E¹, and E². The 15 latter cavities may be filled after the blocks are put in place through the holes thereafter closed by the plugs F. Advantageously the blocks E and E² are formed at their upper sides with laterally projecting flanges, 20 the under sides e^5 of which are horizontal and fit against the upper sides of correspondingly lateral shoulders or ribs formed at the lower edges of the blocks E¹.

Characteristic features of the new construction are;

1. That the refractory blocks composing the refractory body portion of the car are much larger than have heretofore been employed in the construction of such car bodies. As a matter of fact the blocks in the construction shown, are as large as it is ordinarily feasible to make them.

2. The joint surfaces between the different blocks are comparatively few in number, 35 and are all vertical or horizontal. Preferably the blocks after being formed and burnt are dressed to true up the joint surfaces and make possible close joints, and no mortar is used in the joints, and particularly in the vertical joints.

3. The lower tier of blocks D, D¹, D² and 40 D² are interlocked with tier of blocks E, E¹, E², E¹ and E above them against relative lateral movement, either longitudinally of 45 the car, or transversely to its length by the engagement of the ribs e^4 with the end walls d^4 of the channel d^3 , and by the engagement of the web portions e^1 with the shoulders at the inner sides of the surfaces d^5 . In the 50 preferred construction illustrated the blocks D, D¹ and D² are all held together by their engagement with the flange A¹ of the metallic bottom frame member A of the car.

Because of the characteristic features just 55 enumerated the refractory body portion is much less apt to be disrupted or injured by the expansion and contraction of the parts occurring as the car body is heated up and cooled down. With the new construction the 60 parts are all free to expand as the car heats, and when it is thereafter cooled, the parts tend to draw back to their original positions without subjecting any of the parts to disruptive stresses. I thus avoid a characteristic 65 difficulty experienced with refractory

car bodies, as heretofore generally constructed with the bodies made up of comparatively small fire brick units mortared together. In such a structure, on the contraction of the parts, occurring when the car is cooled down 70 from a previous high temperature condition, there is a tendency for the mortar in the vertical joints to drop down in the cracks between adjacent bricks and prevent the latter from drawing together. Mortar thus dropping down in any small joint portion prevents the parts from coming together again, and any initial cracking thus produced ordinarily causes further cracking on a subsequent expansion and contraction of 80 the structure. In consequence it has been necessary in the past to rebuild the refractory portions of tunnel kiln cars with comparative frequency.

In addition to, or in lieu of the interlocking of upper and lower main tiers of the refractory body portion of the cars by interlocking shoulders of the refractory blocks of the tiers interlocked, I may employ metallic clamping posts having a considerably 90 higher tensile strength than clay bodies for this purpose, and in Figs. 4 and 5 I have shown a car structure in which the two main tiers are formed by blocks D¹⁰, D¹¹, D¹¹, and D¹², and blocks E¹⁰, E¹¹, E¹¹, 95 and E¹⁰.

The blocks forming the lower tier in the construction of Figs. 4 and 5 are shown as substantially identical with the blocks forming the lower tier of the cars shown in Figs. 1, 2 and 3 except for the omission of integral interlocking provisions. The blocks forming the second tier of the car shown in Figs. 4 and 5, differ from the corresponding blocks of the construction shown in 105 Figs. 1, 2 and 3 in the omission of integral interlocking with the blocks of the lower tier, and also as shown though not necessarily, in the omission of the shoulders overlapping, in the construction of Figs. 1, 2 110 and 3, at e^5 . To interlock the blocks in the two lower tiers of the cars shown in Figs. 4 and 5, I employ metallic parts I. Each of these parts as shown (see particularly Fig. 6) is cruciform in shape with transverse 115 lugs or shoulders I⁸ at the opposite ends of one pair of opposed arms I¹ of the cross, and with similar lugs I⁸ at the opposite ends of the other pair of arms I² of the cross. As shown there are three of these metallic 120 clamping parts I. One of these parts has its arms I¹ received in a corresponding longitudinal channel formed partly in the upper side of the web portions d^2 of the block D¹⁰ and the adjacent block D¹¹, and partly in the web portion e^2 of the blocks E¹⁰ and E¹¹ above. The arms I² of this clamping part I are received in a corresponding channel extending transversely to the length of the car 125 and formed partly in the adjacent web por- 130

tions *d* and *e* of the four blocks thus interlocked. Each of the four blocks is formed with a socket or recess for the corresponding portions of the lugs *I*³ of the interlocking member *I* for the blocks. A second one of the three interlocking members *I* interlocks the four blocks *D*¹¹, *D*¹², *E*¹⁰ and *E*¹¹ at the opposite end of the car in a manner exactly similar to that described above, and the third interlocking member *I* similarly interlocks the two blocks *D*¹¹ and the three blocks *E*¹¹. It will, of course, be understood that the metallic interlocking members are not necessarily of the exact shape or arrangement shown in Figs. 4 and 5. The metallic interlocking members are advantageously made of cast iron and when made of this material and protected as shown from exposure to the kiln atmosphere they will last almost indefinitely notwithstanding the temperature to which they are subjected. With these metallic interlocking parts, when the car structure heats up the expansion of the metallic interlocking members is slightly greater than that of the refractory blocks, so that the metallic parts do not resist the expansion of the refractory parts. On cooling the contraction of the metallic parts causes them to engage the refractory blocks and draw the latter back into their original positions.

While in accordance with the provisions of the statutes I have illustrated and described the best forms of my invention now known to me it will be apparent to those skilled in the art that changes may be made in the form of the apparatus disclosed without departing from the spirit of my invention as set forth in the appended claims, and that certain features of my invention may

sometimes be used to advantage without a corresponding use of other features.

Having now described my invention, what I claim as new and desire to secure by Letters Patent is:

45

1. A tunnel kiln car comprising a metallic bottom frame member and a refractory body portion mounted thereon, and formed of large blocks of refractory material having close fitted unmortared vertical joints and provisions interlocking blocks in each tier with one another and with blocks in adjacent tiers.

50

2. A tunnel kiln car comprising a metallic bottom frame member and a refractory body portion mounted thereon, and formed of large blocks of refractory material having close fitted unmortared vertical joints and internal provisions interlocking blocks in each tier with one another and with blocks in adjacent tiers.

55

3. A goods carrying car for a tunnel kiln consisting of a metallic frame and a body portion formed of massive chambered blocks of refractory material with the chamber spaces in the blocks filled with a porous heat insulating material.

60

4. A goods carrying car for a tunnel kiln consisting of a metallic frame and a body portion formed of massive chambered blocks of refractory material with openings in said blocks at the top of said body portion through which heat insulating material may be passed into the chamber spaces in said blocks.

75

Signed at Detroit, in the county of Wayne and State of Michigan this 1st day of April A. D. 1920.

PHILIP D'H. DRESSLER.
